Primary Examiner — Elizabeth J Oswecki(74) *Attorney, Agent, or Firm* — Dinsmore & Shohl LLP; Douglas McEvoy(57) **CLAIM**

The ornamental design for a contoured ear protector, as shown and described.

DESCRIPTION

FIG. 1 is a perspective view of a contoured ear protector showing my new design, in a used condition on a human figure shown in broken lines;

FIG. 2 is another perspective view of the contoured ear protector in FIG. 1;

FIG. 3 is a right side view thereof;

FIG. 4 is a top plan view thereof;

FIG. 5 is a front view thereof;

FIG. 6 is a left side view thereof;

FIG. 7 is a bottom plan view thereof; and,

FIG. 8 is a rear view thereof.

The broken lines showing a human figure in FIG. 1 form no part of the claimed design.

1 Claim, 3 Drawing Sheets(56)
